DREDGING APPARATUS.

(Application filed Feb. 5, 1901.)

(No Model.)

2 Sheets—Sheet 2.

UNITED STATES PATENT OFFICE.

JOSHUA L. GARWOOD, OF BUTTE, MONTANA.

DREDGING APPARATUS.

SPECIFICATION forming part of Letters Patent No. 679,738, dated August 6, 1901.

Application filed February 5, 1901. Serial No. 46,094. (No model.)

To all whom it may concern:

Be it known that I, JOSHUA L. GARWOOD, a citizen of the United States, residing at Butte, in the county of Silverbow and State of Montana, have invented certain new and useful Improvements in Dredging Apparatus; and I do declare the following to be a full, clear, and exact description of the invention, such as will enable others skilled in the art to which it appertains to make and use the same.

This invention relates to improvements in dredges or shovels for mining and other excavation work.

One object of the invention is to provide a dredge which is comparatively simple of construction, easily and quickly operated, capable of being conveniently transported, and adapted for both land and harbor work; and a further object is to provide a telescoping dredge which when elevated will automatically discharge the load by gravity, the sections of the dredge serving as conductors through which the load passes to the point of deposit, whereby quickness of operation is insured.

With these and other minor objects in view, which will appear as the nature of the invention is better understood, the invention consists of certain novel features of construction, combination, and arrangement of parts, as will be hereinafter more fully described, and particularly pointed out in the appended claims.

In the accompanying drawings, Figure 1 is a side elevation of a telescopic dredge embodying my invention, showing the shovel lowered for loading. Fig. 2 is a similar view showing the dredge elevated for dumping. Fig. 3 is a top plan view. Fig. 4 is a vertical longitudinal section. Fig. 5 is a cross-section on line 5 5 of Fig. 3.

Like reference characters designate corresponding parts throughout the several views.

The numeral 1 in the drawings represents a base or supporting - column in which is mounted a king-bolt 2, carrying one member of a turn-table 3, on which the dredge is adapted to swing in a horizontal plane and laterally of its carriage, which may be either a boat—such, for instance, as the ordinary dredging-scow—or a car, the other member of said turn-table being fixed to the top of said

base or supporting-column, which in practice is mounted at one end of the scow or car. The king-bolt carries the dredge proper, which 55 is pivoted thereto, as shown at 4, to swing in a vertical plane.

The dredge comprises in its construction a shovel-carrier composed of a relatively fixed or stationary section 5 and one or more telescoping sections 6, the latter carrying the scoop or shovel 7. These sections are composed of comparatively long and narrow boxes or conductors square in cross-section, open at opposite ends, and of such size as to snugly fit 65 one within the other, as clearly shown in Figs. 4 and 5; but it will of course be understood that pipes or conductors of any suitable cross-sectional form may be employed. The section 6 is adapted to slide freely in the section 70 5 and is guided and limited in its movement by longitudinal guide and brace bars 8, mounted to slide in guideways 9 upon the outer sides of the section 5 and connected at their outer ends to the shovel 7 or outer extremity of said section 6. Rollers 10 are provided at the front end of the main stationary section 5 to bear upon the under side of the said sliding section 6 to insure ease of movement of the latter and prevent undue 80 friction and binding. Arranged upon the upper surface of the main section or conductor 5 are guides 11, in which travel a cross-head 12, which is connected to the shovel or outer end of the sliding section or conductor 85 6 by means of connecting-rods 13. The cross-head is connected to the outer end of a piston-rod 14, carried by a piston 15, working in a steam or other fluid pressure cylinder 16, mounted upon the inner end of the main conductor 9 and connected with a steam-chest 90 17, provided with a controlling-valve 18. Steam or other fluid pressure is supplied in practice to the chest 17 through the medium of suitable connections from a boiler or other 95 source of fluid-pressure supply located on the dredge car, scow, or other dredge carrier or support, and the valve 18 is arranged so as to be conveniently operated by an attendant seated upon or stationed near the inner end 100 of the main section 5. The valve is of the three-way type and controls the supply and exhaust of steam. Cushioned stops 19 are provided upon or adjacent to the outer end

of the cylinder to prevent injury by jar or concussion from the cross-head 12 when the dredge is discharging.

The dredge is raised and lowered through the medium of hoisting-cables 20 and 21. The cable 20 is attached at its outer end to a bail 22 upon the shovel 7 and the cable 21 to a similar bail 23 upon the outer end of the sliding conductor-section 6. These cables in 10 a complete organized structure extend back to the dredge-carrier over pulleys suitably arranged and wound around hoisting-drums of different diameters mounted upon a common shaft, said drums being driven by an 15 engine of approved construction.

In operation the dredge is first lowered by the hoisting-cables to the required angle and the sliding section 6 then fed out by admitting steam to the inner end of the cylinder 20 until the shovel or scoop comes in contact with the dirt or ground, when the movement of the cables is reversed and the entire device raised to take up the load. The raising movement is then continued until the shovel 25 passes upwardly beyond the horizontal, when the load passes from the shovel into the sliding section 5, which acts as a chute down which the load flows by gravity and discharges from the inner end of the section 5 30 into the body of the car, hold of the scow, or a suitable receptacle. Upon the admittance of steam to the cylinder the cross-head is forced outwardly under the action of the piston and by means of the connecting-rods 35 projects the conductor-section 6 from its in-closing section 5. When the device is elevated, the section 6 automatically telescopes into section 5.

From the foregoing description, taken in 40 connection with the accompanying drawings, the construction and mode of operation of the invention will be readily understood. By mounting the dredge so as to swing in both a vertical and horizontal plane it will be readily 45 perceived that the device may be readily and conveniently turned for excavating to the right or left of its carriage, and by constructing the parts so as to telescope it will be apparent that the device may be easily 50 handled and valuable space and time economized in transportation.

The invention will be found of great value in mining, owing to its compactness and the

readiness with which it may be moved from place to place and within a minimum amount 55 of space.

The weight of the device may be approximately counterbalanced by weights applied to the cable 21, if desired.

Changes in the form, proportion, and minor 60 details of construction may be made within the scope of the invention without departing from the spirit or sacrificing any of the advantages thereof.

Having thus described my invention, what 65 I claim, and desire to secure by Letters Patent, is—

1. A dredge comprising a main conductor-section mounted to swing in vertical and horizontal planes, a sliding section adapted 70 to telescope therein, said sections adapted to serve as conveyers through which the load is adapted to discharge by gravity when the dredge is raised, a shovel carried by the sliding section, means for guiding and limiting 75 the outward movement of the sliding section, and means mounted upon the fixed section for projecting said sliding section, substantially as described.

2. In a dredge, the combination of a support, a relatively fixed conductor-section mounted to swing in vertical and horizontal planes upon said support, a sliding section adapted to telescope therein, said conductor-sections serving as conveyers for the discharge of the load by gravity therethrough when the dredge is raised, a shovel carried by the sliding section, guide and brace bars 85 slidably connected to the fixed conductor-section and also connected to the sliding conductor-section to guide and brace and limit the 90 outward movement of the latter, means for raising and lowering the dredge, a cylinder mounted upon the fixed section, a piston in said cylinder, a cross-head sliding in guides 95 on the fixed conductor-section and connected to the piston-rod, and connecting-rods between said cross-head and the sliding conductor-section, substantially as described.

In testimony whereof I have hereunto set 100 my hand in presence of two subscribing witnesses.

JOSHUA L. GARWOOD.
